J. H. D. EVERETT,
IRONING BOARD,
APPLICATION FILED APR. 13, 1917.

1,352,361.

Patented Sept. 7, 1920.

UNITED STATES PATENT OFFICE.

JOHN H. D. EVERETT, OF BOULDER, COLORADO.

IRONING-BOARD.

1,352,361.

Specification of Letters Patent.

Patented Sept. 7, 1920.

Application filed April 13, 1917. Serial No. 161,891.

To all whom it may concern:

Be it known that I, JOHN H. D. EVERETT, a citizen of the United States of America, residing at Boulder, in the county of Boulder and State of Colorado, have invented certain new and useful Improvements in Ironing-Boards, of which the following is a specification, reference being had therein to the accompanying drawings.

10 This invention relates to ironing boards and refers more particularly to an ironing board of the folding type and one which is preferably also provided with a sleeve board, although the invention in its broader aspects is not limited to this particular combination.

Among the objects of the invention are to provide an ironing board which is simple in construction and can be economically manufactured but which will have great rigidity; to provide a construction in which the parts, including the sleeve board, can be folded to lie adjacent the main board; to so construct and arrange the parts that when the board frame is opened it will automatically move to its locking position and can be sprung into a securely locked position; to provide a construction preferably of the three-point supporting type in which the standard which engages the floor at two points is first brought back against a permanent abutment and locked in engagement against such abutment when the other parts are sprung into locked position; to provide an improved arrangement for adjusting the board to various heights; to provide a novel mounting of the sleeve board with reference to the main board; to provide improved means for securing the cover for the pad to the board; and in general to provide an improved and simplified ironing board construction of the character above referred to.

The invention also resides in such other details of construction and arrangements and combinations of parts as will more fully hereinafter appear.

In the drawings:

Figure 1 is a side elevational view of an ironing board or table in assembled position;

Fig. 2 is a similar view of the parts in folded position;

Fig. 3 is an end elevational view.

Fig. 4 is an enlarged fragmentary sectional view through the adjustable locking member.

Describing in detail the particular embodiment of my invention shown in the drawings, A designates the main ironing board and B the frame therefor which is 60 preferably pivotally secured to one end of the board by a bolt or other pivot member C. This bolt extends through lugs or projections D and D' permanently fastened to the board and to which lugs there is secured 65 a stationary abutment member E. The standard F is provided with legs G and G' which are pivoted by means of the pivot member C and are so arranged that the rear sides of the legs G and G' strike against the 70 abutment member E when the standard F is swung open to its operative position.

There is also pivotally mounted on the member C a diagonal leg or supporting member H which forms the third leg of the 75 board. Near its center this diagonal leg H has pivotally secured to it a locking bar J. Preferably the diagonal leg member H is formed of spaced portions H' and H² between which the locking member J extends 80 in its folded position. At one end this locking bar J is provided with hooked claws K and K' which fit over a cross bar K² carried by the standard F. The other end of the locking bar is beveled at L and swung into 85 locking engagement with the oppositely beveled end L' of the adjustable locking member L². Suitable screws or other securing devices L³ are employed for the locking member L² whereby the latter can be locked 90 in various positions of adjustment toward or from the stationary abutment E.

The arrangement of parts is such that in opening the board frame, the standard F is swung back until the rear side of its legs 95 strike against the stationary abutment E. The diagonal leg H is then opened and the locking bar swung to a position where its beveled end L extends into engagement with the locking member, while the claws K and K' on its opposite end are sprung into locking engagement with the cross bar K². The portion of the locking bar adjacent the claws K and K' is preferably beveled at M so as to permit the locking bar to ride over the 100 cross bar K² and spring into locking engagement. However, if desired this end can be engaged first and the beveled end L sprung into locking engagement with the abutment L², or if desired the screws L³ can be 105 loosened and the locking member L² tightened up afterward to put the parts under

tension. In every case the locking bar is tensioned so that great rigidity is obtained for the entire device without the necessity of using extraneous fastening means.

5 To permit the board to be adjusted to accommodate the heights of various users, I have provided a novel vertical adjustment. This comprises forming an adjustable base N on the lower end of the standard F and a 10 sliding bar O on the lower end of the diagonal leg H. By loosening the bolts N' and O' these members can be raised or lowered and then locked in the desired position of adjustment by tightening up the bolts N' and O'. Improved means are also provided for securing the pad Q in place. For this purpose the lower surface of the board A is provided with a plurality of eyelets Q' through which there can be laced the securing member Q² 15 for the pad cover Q³.

20 The invention also contemplates an improved construction wherein the iron holder S also serves as a support for the sleeve board T when the latter is in use. The holder board T when the latter is in use. The holder 25 S at its rear end is provided with a raised flange S' which will serve to prevent the iron from slipping off when the opposite end of the board is raised and also has a socket member S² into which the pin T' of the sleeve 30 board T fits. Said socket member has an opening therein with which a lug upon the pin T' may be engaged to hold the sleeve board in one position of rotative adjustment. When not in use the sleeve board is carried by the 35 locking bar J which has a seat J' and a retaining strip J² beneath which the outer end of the sleeve board extends, while the pin T' extends through an aperture T² in the locking bar J and is locked in position by a 40 spring retaining member T³. Thus when not in use the sleeve board is stored where it is out of the way and is also automatically folded against the board A when the supporting frame of the latter is moved to its 45 inoperative position.

50 From the above description it will be apparent that the construction is one which can be economically manufactured and readily adjusted to its various positions, while at the same time it has great rigidity because of the springing of the parts into locked position. Moreover this arrangement permits of a relatively unobstructed lower surface near the free end of the board A, while 55 the three-point support allows it to automatically adjust itself in a firm position irrespective of the level of the floor.

60 Various changes however in the details of construction and arrangements and combinations of parts can be made within the scope of my invention.

What I claim as my invention is:

1. In an ironing table, the combination

with a board, of a three-point supporting frame therefor comprising a standard 65 adapted to engage the floor at spaced points, a diagonally projecting supporting leg, an adjustable abutment secured to said board, and a locking bar having a resilient portion adapting it to be sprung into position between said standard and said adjustable abutment for fastening said standard and leg in fixed position.

2. In an ironing table, the combination 70 with a board, of an abutment member rigidly secured thereto, a supporting frame for said board having a standard pivotally secured to the board and rockable to a position against said abutment, an adjustable abutment also secured to said board, and a locking bar having a resilient portion adapting it to be sprung into locking position between said standard and adjustable abutment so as to press said standard against said abutment when the table is in position of use. 75

80 3. In an ironing table, the combination with a board, of a supporting standard pivoted to one end of said board, a supporting leg pivoted to the same end of said board and occupying a diagonal position in 85 use and a resilient locking bar pivoted intermediately upon said leg, an abutment for one end of said locking bar upon the lower portion of said standard and an abutment 90 for the other end of said locking bar, longitudinally adjustable upon said board to stress said locking bar and secure rigidity. 95

4. In an ironing table, the combination 100 with a board, of an abutment carried by the board, a substantially vertical standard engaging said board adjacent one end of the same, a coacting supporting leg extending diagonally from one end of the board beneath the latter and a member pivoted upon said diagonal leg having a substantially rigid portion at one side thereof for engagement with said standard and having a resilient portion at the other side of the leg engageable with the abutment and adapted to be stressed by such engagement to establish a rigid relation between the board and frame. 110

5. An ironing table including a board equipped with an abutment on its under face and a supporting structure consisting of a supporting standard and a supporting leg secured to said board at a point remote from the abutment and an inherently resilient locking bar pivotally mounted intermediate its ends on said supporting leg, one end thereof being engageable with the supporting standard and the opposite end being flexed beneath said abutment for rigidly supporting said ironing board.

In testimony whereof I affix my signature.

JOHN H. D. EVERETT.
